MEANS FOR LUBRICATING ICE RUNNERS
OR BLADESWilfred B. Vaillancourt, 393 North St., Sault Ste. Marie,
Ontario, CanadaFiled Sept. 8, 1960, Ser. No. 54,664
4 Claims. (Cl. 280—11.12)

The present invention is concerned with improvements in or relating to ice blades or runners such as are used, for example, in skates, sleds and ice boats which are intended for travel upon ice surfaces.

At any temperature between about 10° F. and the freezing point of water a sheet of ice is in equilibrium with a thin adherent film of water covering its surface, which film will reduce considerably the friction of a smooth body sliding upon the ice sheet. If the contact pressure of the body is sufficiently high the film is momentarily thickened over the area of contact and the sliding friction coefficient is reduced appreciably; this well-known effect is understood to explain why ice skates, sleds and ice boats can travel at relatively high speeds over ice with little effort. With ice at between 28° F. and 32° F. the adherent surface film is at its thickest and the lowest sliding friction coefficient is manifested. Such ice is however less strong than a sheet held at a lower temperature.

In a skating arena with artificial ice where the temperature of the ice is controllable, a temperature of about 16° F. is preferred and is maintained to provide ice of optimum hardness and toughness, and to allow ice hockey pucks and other low contact pressure objects to slide easily without sticking.

It was at one time believed that the thickened layer of water under the ice blades or runners provided as much reduction in friction as could be expected, but subsequently it has been proposed to apply a liquid lubricant between the ice and the blades or runners to reduce the sliding friction still further. The result of reducing the sliding friction is to increase the speed possible for a given effort, or to reduce the force required in starting a body from rest and in maintaining it in motion at a predetermined speed.

A primary object of the present invention is therefore to provide a new form of lubricated ice blade or runner, and, in accordance with this invention, this object is achieved by providing an ice blade or runner comprising a blade member having an ice-engaging face, a reservoir for a lubricant liquid, and liquid flow control means for adjusting the rate of flow of liquid from the reservoir along a flow path to the ice-engaging face.

Another object of the present invention is to realize a skate or runner having relatively thin blades whose ice contacting surface is lubricated, and to this end an ice blade or runner is provided comprising a blade member having two side faces and an ice-engaging face, a reservoir for a lubricant liquid and at least two liquid flow control means for adjusting the rate of flow of liquid from the reservoir along respective flow paths over the side faces to the ice-engaging face.

A particular form of ice skate blade intended primarily for playing ice hockey will now be described, by way of example, with reference to the accompanying drawing, wherein:

FIGURE 1 is a view in side elevation of the skate having a reservoir and liquid flow control means according to the invention;

FIGURE 2 is a section taken on the line 2—2 of FIGURE 1 and drawn to a larger scale, and showing one form of liquid lubricant flow control means; and,

FIGURE 3 is a sectional view taken on line 3—3 showing an alternative flow control valve means.

2

Referring now to FIGURES 1 and 2, an ice skate blade of conventional form is shown, comprising a blade member 10 of rectangular section mounted securely as by welding or brazing in a longitudinal slot in a hollow, tubular frame member 11. Two hollow frusto-conical support posts or columns 12 and 13 extend upwards from the tubular member 11 and carry respectively at their upper ends sole-supporting plate 14 and heel-supporting plate 15. The plates 14 and 15 are intended to be fastened to a skate boot (not shown) in known manner, as by screws or rivets. The front end of the skate member 10 is also fastened to the sole plate 14 by means of a bracket 16 and rivets 17.

The interiors of the posts or columns 12 and 13, and of the tubular member 11 are in free communication with one another, as by apertures 37, formed in the upper part of tubular body 11, and together form a single reservoir for holding a quantity of liquid lubricant as indicated at 39. An apertured breather plug 18 is provided in the column 13 and/or the column 12, the plug being of a form and provided with a capillary bore (not shown) such as will permit air to flow into the reservoir and yet prevent liquid from escaping whenever the skate is held on its side. In this embodiment the plug 18 is also readily removable as by threaded engagement in a hole in the wall of column 12 to provide a filling aperture through which the reservoir may be filled with lubricant liquid. It is to be understood that in other embodiments a separate filling plug may be provided and that more than one breather plug 18 may be also provided.

Flow control means for the liquid lubricant according to a preferred embodiment are shown in detail in FIGURE 2 and comprise two separate valve assemblies each of which controls the flow of liquid in a respective flow path from the interior of the reservoir to the blade edge. Liquid which has reached the junction of the side face of the blade 10 with the ice surface 41 moves by capillary action as a film wetting running surface 10a to provide a thin lubricating layer (not shown) on which the concave blade slides. Each valve includes a tubular housing or body 19 which extends through the hollow member 11, with its longitudinal axis inclined to the vertical when the skate is in its normal upright position. The axis of housing 19 may conveniently be inclined at 45° from the vertical, although somewhat greater or lesser angles of inclination may be employed. The housing 19 is fixed in the member 11 by any suitable means, for example by welding or upsetting its ends in apertures 22a formed by drilling through both walls of the frame along a diameter. A screw 20 is coaxially mounted in the housing, engaging a correspondingly screw-threaded bore 20a intermediate the ends of housing 19. The screw 20 has a tapering pointed end 21 which extends into an axial counterbore 22 of lesser diameter adjacent the lower end of the body, thereby constituting a flow-controlling needle valve. A restoring spring 23 is engaged beneath the head of the screw in bore 20b to ensure that the screw cannot turn accidentally due to vibration and shock.

A transverse bore or port 24 through the housing intersects the axis of bore 20a at its junction with counterbore 22, thereby providing a passage in communication with the interior of the reservoir. With the screw 20 seated "home" at the junction with bore 24, liquid cannot escape from the reservoir and the rate of flow is controllable by withdrawing the point of the screw from this "home" position to a desired setting. The liquid passing into the counterbore 22 is led therealong to an aperture 22a and flows down by way of a channel 25 in the side of tubular member 11 and thence down the side of blade 10. The liquid reaches the contact zone between the blade and the ice surface and so lubricates the contact.

A shallow groove or channel 40 may also be provided in the side face of the blade member 10 transversely of its length to provide a more definite flow path for the liquid. Such a channel may however be omitted in favour of unguided downward movement of liquid over the side faces, particularly where blade 10 is very thin.

The other of the said two valve assemblies comprises a second tubular body designated 19a also extending through the tubular frame member with its longitudinal axis at 45° to the vertical, but oppositely inclined to the first valve. Liquid flowing from valve body 19a is led in its respective flow path by a channel 25a and thence down the other side face of blade member 10. While two separate valve mounting bodies 19 and 19a are disclosed for the embodiment described, more than two valves and their associated flow paths may be provided in other embodiments not illustrated herein. It is believed to be apparent that such additional valves and flow paths may be arranged as desired along a frame member to discharge liquid lubricant to the running surface at a point or points so that as much lubricant may be supplied as may be found necessary. Such a modification is contemplated as being particularly applicable to lubrication of sled and ice yacht runners of considerable length running at high speed.

Preferably, the heads of the plugs 18 and the screws 20 are slotted to receive a coin, a screwdriver blade, or other manipulative tool whereby they can be turned to adjust flow rate of the liquid. In the embodiment illustrated the heads of the plugs and screws are shown as standing slightly protruding from the skate blade members, although in other embodiments they may be set in recesses sufficiently deep to ensure that they are not struck by hockey sticks or other skates while in use.

The interior surfaces of the tubular member 11 and the exterior surfaces of the valve bodies 19 and 19a are preferably coated with a liquid-impervious layer 26, e.g. of polyethylene applied as a coating from a liquid melt, which serves to aid in the prevention of corrosion and rusting of these surfaces. The layers 26 may not be required where the reservoir and flow control devices are fabricated of nonrusting materials, such as stainless steel or aluminum, for example.

In those embodiments adapted to existing forms of tubular hockey skate having apertured sole and heel plates 14 and 15, it is advisable to employ suitable sealing means between the boot and the reservoir space to prevent loss of liquid or damage to the boot sole.

Referring now to FIGURE 3, another form of flow control means is illustrated in which a single tubular body 27 is mounted transversely horizontally in the tubular frame member 11. A screw-threaded bore 38 extends the length of tubular body 27 and contains a plug 28 of resilient porous compressible material disposed intermediate the ends of the body between the two screws 29 and 29a threadedly received in the body ends. Each screw has a respective axial bore 30 and 30a, one end of each bore being in contact with the plug 28 and the other end being open to communicate with the aperture 22a in the skate frame member. By movement of the two screws in an axial direction to compress the plug 28 between them, the porosity and hence the flow capacity of the plug material for conveying liquid from the reservoir to bores 30 and 30a is decreased, and may be brought to zero by sufficiently compressing the plug. Retraction of the screws 29 and 29a permits reservoir fluid to enter tubular body 27 through side port 31 and to flow through the plug, and thence by way of bores 30 and 30a down channels 25 and 25a to flow down the opposite side faces of blade member 10 to the running face 10a. Any suitable number of such valve devices may be provided along the length of a blade or runner.

Two or more ports 31 may be provided in the wall of tubular body 27 to expedite movement of liquid into plug 28. The latter is preferably formed as a jumbled

mass of filaments of a durable non-swelling substance such as one of the polyamides known in the trade as "nylon," or a suitable polyester material.

Suitable lubricating liquids are clear water, preferably having a low concentration of dissolved salts and suspended matter. Emulsions of the water-in-oil type and substances in the nature of wetting agents are however preferred to water alone for the reason that such materials have advantages of greater lubricity and/or lower surface tension, thereby promoting the flow and spreading of lubricant liquid along the running surface. Desirable additives are non-ionizing organic polyhydroxy compounds such as glycerol and several of the soluble polyols having the property of lowering the freezing point of a solution containing them.

One composition found to be highly effective as a lubricant and having other desirable use properties, was composed of an emulsion in water of a light mineral oil with a metallic sulfonate emulsifier. This was produced by mixing approximately five volumes of water with one part of a product known as "Veltex 1000," the latter being composed of from 5 to 25 percent by weight of a metallic sulfonate emulsifier with from 95 to 75 percent of petroleum lube oil in a viscosity range from about 10 to about 30. Various glycol type emulsifiers may alternatively be employed or may be added to the Veltex product, for example ethylene glycol may be a constituent.

The amount of liquid reaching the ice surface is very small and no disadvantageous effects have been found to arise from its use. The modification of conventional tube and column forms of hockey skate structure as described provides a reservoir of ample capacity for long periods of skating. While the invention has been specifically illustrated as applied to known skate structures it is to be understood that the reservoir volume may be greatly increased and in addition detachable tanks may be disconnectably connected in lieu of filling the reservoirs through filling plugs 18.

Although in the embodiments described the liquid lubricant is led to the running surface via flow paths on opposite side faces, a groove 40 may be cut to such depth adjacent the lower margin of each side face as to apply the liquid more directly along the running face 10a. To preserve blade or runner strength, a fine bore (not shown) may be passed obliquely from the running face 10a upwardly to intersect the groove 40 on one side face only, and the valve set to discharge to that side only.

In illustration of the efficacy of the present invention a test was carried out employing a fresh, smooth ice sheet at 16° F. on which a pair of skates were supported in parallel and loaded equally with 200 pounds load on each. A horizontal pull was applied to accelerate the skates to a sliding speed of 180 feet per minute, after which a constant speed was maintained, and the pull measured. The test was repeated with a plain water lubricant, and with a water-oil emulsion as described. The respective pulls required to sustain speed of 180 feet per minute were 8 pounds, 3 pounds, and 2.6 pounds.

Various other embodiments of the invention will readily suggest themselves in applying the teachings set out hereinbefore, within the scope of the appended claims.

I claim:

1. An ice blade comprising a longitudinal blade member providing an ice-engaging face and a pair of side faces, a longitudinal tubular member in which the blade member is supported, said member providing a reservoir for a liquid lubricant, an opening in said tubular member communicating with said reservoir, liquid flow control means for adjusting the rate of flow of liquid from said reservoir through said opening, and a liquid guiding channel formed in the exterior surface of said tubular member for guiding said flow of liquid along a flow path from said opening over a side face to the ice-engaging face.

2. An ice blade as claimed in claim 1 wherein the said flow control means comprises one or more valve bodies secured in a respective opening in said tubular member having coaxial threaded bores and having their bore axes inclined from the vertical, one end of each of said bores being disposed external to said reservoir, port means in said valve body communicating with said reservoir and with said bore, and screw needle valve means threadedly engaged in said bore for controllably regulating the flow of liquid from said port through said valve member to said external end.

3. An ice blade as claimed in claim 1 wherein the said flow control means comprises a valve body transversely mounted in said tubular member, a bore in said valve body extending therethrough and opening at its ends externally of said tubular member, an internal thread formed in said bore, a plug of resiliently compressible material pervious to said liquid lubricant filling

10
15

said bore intermediate the ends of said valve body, valve control means threadedly engaged in said bore and movable axially therein upon relative screw rotation to engage said plug whereby to vary the compression of said material, port means in said valve body for conveying said liquid lubricant from said reservoir into said plug, and respective bores in said valve control means for conveying liquid between said plug and said liquid guiding channels.

4. An ice blade as claimed in claim 1 wherein said longitudinal blade member has its side faces grooved to provide a liquid flow guiding path between said channel and said ice-engaging face.
